UNITED STATES PATENT OFFICE.

ALEXANDER CRAWFORD CHENOWETH, OF NEW YORK, N. Y.

METHOD AND APPARATUS OF PRODUCING CEMENTITIOUS ELEMENTS.

1,101,727.

Specification of Letters Patent. Patented June 30, 1914.

Application filed July 23, 1910. Serial No. 573,374.

To all whom it may concern:

Be it known that I, ALEXANDER CRAWFORD CHENOWETH, a citizen of the United States, and a resident of New York city, borough of 5 Manhattan, in the county of New York and State of New York, have invented certain new and useful Improvements in Methods and Apparatus of Producing Cementitious Elements, of which the following is a specification.

My invention relates to new and useful improvements in methods and machines for the formation of cementitious elements, such as beams, posts, poles, sheet piling, and the like, and more particularly to methods and machines which form the element by rolling the same into completed form from a substantially flat sheet of cementitious material, such, for instance, as shown in my prior 20 Patent No. 795,556 and my pending application Serial Number 546,499, filed January 5th, 1910. In the patent and application referred to means is shown for forming a cylindrical or round element by rolling a 25 sheet of cementitious material upon itself, suitable reinforcing means being employed in order to stiffen the product and maintain the same intact.

The primary object of the present invention is to provide means in connection with such a machine whereby the rolling process may be employed in order to produce a polysided element, for instance, one which is square in cross section and one which will 35 permit of producing upon the exterior surface of the element any configuration which may be desirable, either for the purposes of ornamentation, or mechanical reasons.

The invention consists in the improvements to be fully set forth hereinafter and the novelty of which will be particularly pointed out and distinctly claimed.

I have fully illustrated my invention in the accompanying drawings to be taken as 45 a part of this specification, and wherein,

Figure 1 is a view in front elevation of a machine embodying my present improvement; Fig. 2 is a cross section on the line 2-2 of Fig. 1; Fig. 3 is an enlarged detail 50 view in end elevation of the forming platform and the element-forming means thereon; Fig. 4 is a cross section through the forming means and an element contained therein being formed thereby; Fig. 5 is a 55 view in side elevation of a section of the

mold or forming means; Figs. 6 and 7 are cross sections through different forms of elements and face plates of the forming elements necessary to produce said elements; Fig. 8 is a detailed view of the joint for connecting the sections of the forming molds or means.

Referring to the drawings by characters of reference, A designates as a whole the base frame upon which the parts and mechanisms of the machine embodying my present invention are grouped in operative combination. The specific construction of this frame is immaterial as long as it performs the functions for which it is employed, but I prefer to construct the same in the form of a substantially oblong ground frame comprising longitudinal side members 1, 1 joined to each other at their ends by end transverse members 2, 2 and by intermediate transverse members 3, 3 spaced apart from each other, as shown in dotted lines in Fig. 1. Rising from the ends of the members 1, 1 are vertical standards 4, the upper ends of which support upper transverse members 5 and longitudinal upper members 6, the end members 2 having arranged thereon standards or pillars 7 arranged between the standards 4, 4 and also supporting the upper transverse members 5. Connecting said transverse members 5 and running longitudinally of the frame is a central member 8 which performs a function to be presently set forth. In Fig. 1 the end vertical members 4 are broken away at their lower portions so as to clearly disclose the parts of the mechanisms located between the said end members. At each end of the base frame are also supported a pair of vertical standards 9 which support mechanisms to be presently described. Extending transversely of the main frame are pairs of trackways 10, 11 and 12 arranged parallel to each other, one of said trackways being located at approximately the center of the base frame, and one at each end portion of the latter. Disposed longitudinally of the frame and movable bodily transversely, or from front to rear thereof, is a forming table or platform upon which the cementitious body or element is formed. This table is provided with track wheels 13 which run on the trackways above described, and said table is formed with an upper receiving or forming surface 13 to receive the material from which the cementi- 105 110

tious element is to be made this surface being inclined upwardly from the front to rear thereof, as clearly shown in Figs. 2 and 3.

In the upper surface of the forming table 5 is a recess or pocket 15 in which is located a plurality of supporting devices, each consisting of a block or ridge 16 extending from front to rear of the table and formed on its upper surface with a plurality of arc-shaped 10 recesses 17 arranged in series, said blocks or ridges being spaced apart a suitable distance lengthwise of the recess and arranged parallel to each other. It will be noted that the recess does not extend the entire width 15 of the table from front to back, but is of such width that receiving surfaces for the sheet of material from which the body is formed are provided on either side of the recess at the front and rear of the table, as 20 shown at 18 and 19. The recess or pocket and the supports thereon are adapted to receive a collapsible and foldable forming means which might be termed a mold box, which is adapted to be laid out in extended 25 form in said recess, so that the surface of the mold forms a substantially continuous surface with and connecting the surface 18 and 19, the molding means being supported upon the concave or arc-shaped surfaces of 30 the blocks or ridges 16, arranged in said recess, in a manner which will be presently set forth.

I will now proceed to describe in detail a preferred form of molding means which 35 I have found particularly adapted for attaining the desired results, but before doing so I desire it understood that I do not wish to be limited to any particular construction of the mold box. This mold box may consist of a plurality of sections 20 laid end to end in longitudinal alinement and each of 40 which consists in the embodiment shown of four walls, each of which is provided with rockers 21 which walls are adapted to be connected to form a mold rectangular in cross section, said rockers being spaced apart lengthwise of the wall equal to the distance between the blocks 15, and each adapted to 45 rest within one of the arc-shaped seats in the said supporting blocks located in the recess 15 the rockers on the walls being arranged so that when the mold is folded or closed, said rockers at corresponding points on the walls form a continuous substantially 50 circular surface, as shown in Fig. 4 of the drawings. It will be seen that by forming the seats 17 to conform substantially to the form of the rockers that the latter are held so that the mold walls do not rock while 55 the machine is operating, and the upper surfaces of the said walls of the mold are at all times maintained in substantially the same plane. The mold parts are detachably connected to each other by hinge bars 22, arranged within hinged plates 23, secured re-

spectively on the meeting edges of the mold boards, the hinge plates and bars serving to form a pivotal connection between the adjoining edges of the mold boards and also providing detachable means whereby said boards 70 may be separated to permit the parts being laid out flat, the hinge bars being removable by a longitudinal movement from said hinge plates to disconnect the latter. The mold box sections may be of any desired length 75 and may be supplied with any number of these rockers which may be desired. The rockers located at the ends of each mold section, as shown in Fig. 8, are provided with a plurality of apertures 24 which when the 80 sections are in proper relation to each other aline and are adapted to receive connecting pins 25 by means of which these sections are locked together. It is not absolutely essential that this mold box be made in a plurality of sections, but it is advantageous in that it permits the formation of an element of any desired length and by opening any particular sections, permits inspection of that part of the body being formed without 85 disturbing the other sections. The interior surfaces of the mold box may be formed with any configuration which it is desired to give to the element formed either for mechanical or ornamental purposes. For instance, in Fig. 4 I have shown an element 90 adapted to be used for the construction of sheet piling and this mold is provided upon the interior surface of one of its boards with a projection 26 and on the interior surface 100 of the opposite board with a recess 27, so that the element when formed is provided on one side with a recess and the other side with a tongue, the tongue and recess being adapted to coöperate with corresponding parts 105 formed in other elements.

Other forms of interlocking surfaces may be employed without in any way departing from the spirit of my invention, such, for instance, as shown in Figs. 6 and 7.

Mounted at each end of the frame upon the vertical members 9, 9, is a sliding frame 29 and in each of these frames is journaled a chuck shaft 30 carrying at its inner end a chuck 31 adapted to receive a mandrel 32, 115 which is preferably constructed of two parts 32^a, 32^b laid face to face, as shown in Figs. 3 and 4, said chuck heads being so arranged that the mandrel is supported in a horizontal plane above and extending longitudinally of the forming table. Each of these mandrel shafts carries a gear 33 which in turn meshes with a smaller gear 34 on a shaft 35 journaled in said vertical movable frame and carrying a gear 36 which meshes 125 with a gear 37 on a third shaft 38 also in the frame above the shaft heretofore mentioned and having mounted thereon a sprocket wheel 39 over which passes a sprocket chain 40 by means of which the 130

shaft 38 is driven from a power shaft 41 carrying a sprocket wheel 42 engaged by the said sprocket chain. By this means it will be seen that both of the chuck shafts 5 may be driven simultaneously from the power shaft 41 and in the same direction. The shafts 38 may be provided with hand cranks 43 by means of which the mandrel may be driven from either end of the machine when desired to operate the same independently of the power. The two sets of 10 gearing are shown as being substantially identical, but the particular construction of the gearing, or its arrangement, is not essential, the only requirement being that the gears be so arranged and constructed that both ends of the mandrel be driven at the same speed and in the same direction.

Before going into any further details of 20 construction I will now describe the operation of the machine as it has so far been disclosed, and the method of procedure in forming a cementitious body. Referring particularly to Fig. 3 of the drawings, it being understood that it is the purpose to produce a reinforcing element, the reinforcing means of which consists in part of a mesh fabric, I would state that I first lay a proper reinforcing fabric, such as wire 25 mesh M, upon the surface 19 of the forming table and extend the same over the upper surfaces of the mold boards which have previously been arranged within the pocket in the forming table with their rockers disposed within the arc-shaped recesses in the 30 blocks of said pockets, the fabric preferably extending entirely across said boards and terminating at approximately the edge of the block at the lower edge of the pocket. 35 Before placing the fabric on the table a plurality of spaced wires W are connected thereto, the spaces between said wires being equal to the spaces between the sets of rockers on the mold box and these wires are arranged over the upper surfaces of the arc-shaped recesses in said pocket beneath the 40 curved surface of each rocker, the free ends of the wires being carried out below the outer edge of the lowermost mold board and connected to the lower edge of the forming 45 table as shown at 44. The parts being arranged as just set forth, the cementitious material of which the element is to be formed is spread over the surface of the reinforcing fabric both at that part arranged over the surface and over the upper surface of the mold board, reinforcing bars 45 having previously been laid upon the upper surface of the fabric and connected thereto if 50 desired. It will be understood that the upper end of the fabric, or that edge which is located over the surface 17, is connected to the mandrel between the parts of the latter, the table having previously been 55 moved forward until the surface 17 is be-

neath the mandrel. The mandrel is then rotated in the direction of the arrow in Fig. 3, which will serve to roll up the fabric and the sheet of material thereon in convolute form, the pull on the fabric serving 60 to move the forming table rearward until the pull on the wires serves to lift the first mold board out of the pocket in the forming platform into the position shown in Fig. 3 and the continued rotation of the 65 mandrel serves to continue the movement of the table toward the rear and successively pick up and turn over the mold boards until they assume the position shown in Fig. 4, forming an inclosed rectangular mold with- 70 in which a body is formed, the exterior configuration of which corresponds to the interior form of the mold, said body having a reinforce of fabric in convolute form. The meeting ends of the first and last mold 75 boards may then be connected by means of the insertion of a hinge bar, whereby the body formed is securely held within the mold which in its closed condition may be rolled away on the circular surfaces formed 80 by the rockers to any desired place where the body may be permitted to set within the mold, the wires having previously been disconnected from the lower edge of the table. In the above operation it will be seen that 85 the portion of the layer of material over the flat or rigid portion of the table is first wound in convolute form on the mandrel and then the continued rotation of the mandrel serves to pick up successively the flexibly connected mold boards, the fabric and material thereon being wound on the mandrel in convolute form and the mold boards 90 successively applying pressure to the soft material to form the faces thereof. 95

In order to assist in giving a post the desired shape and for closely compacting the material about the mandrel, I employ what I term a "hold-back roll" which also serves to hold the post against rolling down the 100 incline of the table, said roll being supported in front of the mandrel, or at that side toward which the formation of the post takes place. The hold-back roll 46 extends longitudinally of the mandrel and is supported so as to be in surface contact with the work, but out of contact with the table. Any suitable support may be employed for the hold-back roll, but I prefer to journal the same in the free end of swinging arms 110 115 47 which are hinged preferably to the vertical post 4 heretofore described as shown at 48. Suitable means is provided for adjusting the elevation of the hold-back roll and for lifting the same free from the mandrel. 120 For the purpose stated, I may employ simple forms of blocks and tackle, as shown at 49, the same being connected to the roll supports and the overhead frame 8. The lines for each tackle run over guide-wheels 50 on the 125 130

overhead frame, thence under a guide-wheel 51 on the base frame to a block 52 depending from the superstructure.

It will be appreciated that whenever one of the mold sections is lifted, due to the rotation of the mandrel that the same tends to lift the mandrel vertically, and I provide simple means for moving the gearing so that the chuck shafts and the mandrel will 10 move vertically simultaneously, whereby any tendency to destroy the connection between the mandrel and chuck shafts, or to otherwise injure the parts or bend the work is avoided. This is accomplished by having 15 the driving mechanism for the chuck shafts mounted on the vertically movable frame, as heretofore described, and the side members of these frames include vertical racks 53 which are engaged by pinions 54 mounted 20 on horizontal shafts 55, the latter at their inner ends being provided with arms 56 connected by a link 57 with a rocker arm 58 mounted on a horizontal shaft 59, from which extends a vertically disposed tappet 25 lever 60, the upper end of which is located adjacent the side adjacent the gearing table. At the sides of the table adjacent each of the points at which the hinges of the mold box are arranged is a projection 61, which, during 30 the movement of the table, strikes said tappet arm at approximately the time each mold board as it is lifted assumes a vertical position, and thereby swings the tappet arm which, through its connection with the sliding gear frame, lifts the latter with the mandrel when the latter moves upwardly.

In order to provide for proper engagement between the wires heretofore described, and the rockers on the mold sections, said 40 mold sections may each be provided with a longitudinal groove 62 which, when the mold sections are folded, aline to form a continuous groove around the mold box. The spaced wires W referred to may be used 45 to tie the mold sections together by taking the free ends thereof and connecting them in any desired manner to the parts of the wires passing around the rockers.

Having thus described my invention, what 50 I claim as new and desire to secure by Letters Patent is:—

1. The method of forming solid plastic columns, posts, piles and similar bodies having a plurality of faces disposed at angles

to each other, which consists in placing a 55 layer of the body-forming material on a sheet of flexible fabric, winding a portion of the fabric and material supported thereon in convolute form, continuing the winding and simultaneously with the continuance of 60 the winding applying to the fabric and material mold boards disposed in angular relation to each other.

2. In a machine for molding plastic columns, posts, piles and similar bodies, a mandrel, a table beneath the mandrel, a recess in the table, a plurality of hingedly connected mold-forming members in said recess, said table and members being adapted to receive material to be molded, the upper surfaces of 70 said members being substantially flush with the upper surface of the table and means whereby rotation of the mandrel folds the said members to form a mold to inclose said material.

3. In a machine for forming plastic columns, posts, piles and similar bodies, a forming table and a mandrel movable relative to each other, said table having a fixed, rigid forming surface and a flexible forming surface adjoining each other and constituting a continuous platform to receive a layer of material to be molded, and means for revolving the mandrel to wind the said layer of material thereon and means connected to the 85 mandrel and extending beneath the flexible forming surface for folding the flexible surface to inclose the material about the mandrel.

4. In a machine for forming plastic columns, posts, piles and similar bodies, a forming table and a mandrel movable relative to each other, a flexible mold on the table consisting of flexibly connected members to receive a layer of cementitious material, and 95 means connected to the mandrel and extending beneath said flexible mold to lift the latter and fold it about the mandrel when the table and mandrel are moved relative to each other.

In testimony whereof I have signed my name to this specification in the presence of two subscribing witnesses.

ALEXANDER CRAWFORD CHENOWETH.

Correction in Letters Patent No. 1,101,727.

It is hereby certified that in Letters Patent No. 1,101,727, granted June 30, 1914, upon the application of Alexander Crawford Chenoweth, of New York, N. Y., for an improvement in "Methods and Apparatus of Producing Cementitious Elements," an error appears in the printed specification requiring correction as follows: Page 1, line 109, for the reference number "13" read *14*; and that the said Letter Patent should be read with this correction therein that the same may conform to the record of the case in the Patent Office.

Signed and sealed this 4th day of August, A. D., 1914.

[SEAL.]

J. T. NEWTON,

Acting Commissioner of Patents.
